W. HARRISON

LIGHTING FIXTURE

Filed Jan. 8, 1921

Fig. 1

Fig. 2.

INVENTOR:
WARD HARRISON,
BY *Almon G. Davis*
HIS ATTORNEY.

UNITED STATES PATENT OFFICE.

WARD HARRISON, OF CLEVELAND, OHIO, ASSIGNOR TO GENERAL ELECTRIC COMPANY, A CORPORATION OF NEW YORK.

LIGHTING FIXTURE.

Application filed January 8, 1921. Serial No. 435,824.

To all whom it may concern:

Be it known that I, WARD HARRISON, a citizen of the United States, residing at Cleveland, in the county of Cuyahoga, State 5 of Ohio, have invented certain new and useful Improvements in Lighting Fixtures, of which the following is a specification.

My invention relates to lighting units and more particularly to units for semi-10 indirect lighting.

The lighting unit disclosed in this application is an improvement on the lighting unit disclosed in my application, Serial No. 360,774, filed February 24, 1920. My object 15 is to secure the advantages of semi-indirect lighting, that is, illumination in which the greater part of the lighting comes from large expansive ceilings, without its recognized disadvantages. The usual way of se-20 curing indirect illumination is to suspend an open bowl of opal or translucent glass below the ceiling and to place therein clear bulb incandescent lamps. One disadvantage of this method is that dust collects 25 rapidly in the open bowl and on the exposed lamps and seriously interferes with the efficiency of the unit. Another disadvantage is that with the concentrated filaments now commonly used in incandescent 30 lamps, the edge of the bowl throws a sharp shadow on the ceiling or on the high side walls and undesirable shadows of the chains or other supports for the fixture appear which detracts from the appearance of 35 the installation. In previous endeavors to eliminate shadows a great sacrifice in the efficiency of the unit has resulted.

In my application, Serial No. 360,774, I have disclosed a semi-indirect unit which 40 is dust proof and from which the disagreeable ceiling shadows have been excluded. That unit is made dust proof by using a totally enclosing glass globe which is covered by a cap. The upper surface or neck 45 of that globe is of clear glass but of a steep slope so that the dust can slide off, and this surface is the only exposed surface which can be materially affected by dust accumulations, the incandescent lamp being 50 enclosed and the bowl of the globe enameled to reflect a majority of the light rays upwardly through the clear glass neck. The efficiency is further increased by using an 55 opal cap over the bowl of the lamp to reflect the light upwardly through the clear

glass neck of the globe. That unit is made shadowless by fringing off the enameled surface of the bowl into the clear glass of the neck of the globe and by making the ceiling pan of the unit proportional to the cap which is placed over the globe. Glare is eliminated from the previous unit of my invention by constructing the upper portion or neck of the globe of such curvature that rays of light which strike the curved surface are reflected back into the enameled bowl of the globe instead of being reflected out into the room.

In a unit embodying my invention which is the basis of this application, I have provided a globe of more pleasing outline. As before, the bowl of the globe is covered with enamel which is fringed off onto the transparent neck of the globe. The neck of the globe is of such curvature that light rays 70 are reflected back into the eyes of an observer. In order to prevent this, I have provided a diffusing shield of such shape and so positioned that light rays which strike the neck curvature are reflected to 75 the shield which directs the light downward into the bowl of the globe and so prevents the rays from passing outwardly through the clear glass portion of the globe and into the eyes of an observer.

Other advantages and objects of my present invention will be more fully explained in the following specification and in the accompanying drawing in which Fig. 1 is a front elevation partially in section of a lighting 80 unit embodying my invention and Fig. 2 is a front elevation of a modification thereof.

In this unit, the cap 10 is fastened to the cylindrical column 11 of the ceiling pan 12 by means of the bolts 13. A glass globe 14 is fastened to the cap 10 by means of the screws 15. A bowl-enameled incandescent lamp 16 is supported in the globe 14 by a socket 17 which is attached to the wiring conduit 18 which in turn is attached to a plate 19 soldered to the cylindrical column 11.

The bowl 20 of the globe 14 is enameled to serve as a partial reflector and appears translucent by transmitted light. The neck 21 of the globe 14 is clear to permit an unobstructed transmission of the light from the lamp 16 to the ceiling. The zone 22 between the bowl and the neck is enameled so that the enamel shades off or fringes off from the bowl to the neck for the purpose of prevent- 105 110

ing a sharp contrast on the ceiling between the light from the neck and the light from the bowl as fully explained in my application, Serial No. 360,774, previously mentioned.

The bowl 20 is shallow but the neck 21 is steep to prevent, as far as possible, the accumulation thereon of dust which tends to slide off so that the unit is but little affected thereby. It is obvious of course that no dust can enter the unit. The incandescent lamp 16 as previously stated, is bowl-enamored which means that the bowl 23 of the lamp is coated with an enamel which primarily reflects a majority of the light rays incident thereon but allows a small portion to be transmitted. Any means of reflecting the major portion of the light upwardly from the bowl of the lamp, such as a reflecting means surrounding a portion of the bowl of the lamp, may be used. In this way the amount of light that falls upon the bowl 20 of the globe 14 is comparatively small and decorative designs placed on the enamored bowl are pleasingly lighted but not to an intensity detrimental to the optical perception of the design.

In order to prevent light rays such as the ray AB, which passes from the light source A to the point B on the neck of the globe, from being reflected from the neck along the line BC passing through the neck of the lamp 16 and the clear glass neck 21 of the globe and so into the eyes of an observer, a deflecting shield 24 is placed around the neck of the lamp 16 and extends upwardly and outwardly until fastened to the cap 10. The effect of the shield 24 is to intercept such rays, the ray BC being intercepted, for instance, at D on the surface of the shield 24. The ray BD is then deflected downward along the line DE into the enamored bowl

20 of the globe. Thus no light is permitted to pass directly from the globe toward the eyes of an observer without being properly diffused.

As disclosed in my application, Serial No. 360,774, previously mentioned, the ceiling pan 12 is of such size that light which passes from the concentrated filament A of the lamp 16 throws the shadow of the cap 10 upon the ceiling pan 12 and substantially covering it. The effect is to cause the contrast between the lighted ceiling and the shadow cast by the cap 10 to be lost in the natural contrast between the lighted ceiling and the ceiling pan which is ordinarily constructed of comparatively dark material.

In Fig. 2 is shown a modification of a light unit embodying my invention in which the cap 25 is attached to the ceiling pan 26 by means of a chain 27, the relative proportion of the cap 25 to the ceiling pan 26 being maintained as before.

What I claim as new and desire to secure by Letters Patent of the United States, is:—

In a lighting unit, the combination with an incandescent lamp and a support therefor, of a globe totally inclosing said lamp and comprising a substantially disc-shaped lower non-transparent bowl portion and a substantially conical upper transparent neck portion, and a deflecting shield interposed between the neck portions of said lamp and of said globe, said parts being so proportioned and arranged that substantially all light rays reflected from one side of the neck portion of the globe toward the opposite side will encounter said shield and be deflected into the bowl portion of said globe.

In witness whereof, I have hereunto set my hand this 30 day of December, 1920.

WARD HARRISON.
